UNITED STATES PATENT OFFICE

2,486,679

DIAPHRAGM TYPE ELECTROMAGNETIC
SIGNAL DEVICE

Peter C. Reck, Adrian, Mich., assignor, by mesne assignments, to Sperti Faraday Inc., a corporation of Ohio

Application January 8, 1947, Serial No. 720,798

1 Claim. (Cl. 177—7)

1

This invention relates to vibratory diaphragm type of electric signalling means.

This invention has utility when incorporated in sound generating devices of the electric horn type. The assembly is in a rugged compact unit with a yieldably mounted actuator in conjunction with an adjustable control therefor.

Referring to the drawings:

Fig. 1 is a front view of the unit assembled in a projectorless horn;

Fig. 2 is an enlarged view of the horn of Fig. 1, from the back or mounting side thereof, a portion being broken away;

Fig. 3 is a still further enlarged view of a fraction of the unit from the left of Fig. 2;

Fig. 4 is a fragmentary view from the right of Fig. 3, showing the yieldable mounting for the coil and the adjustment for the spring tongue of the breaker switch;

Fig. 5 is a partial side elevation of the unit of Fig. 2, broken away to show the circuit breaking switch in side elevation; and

Fig. 6 is a wiring diagram of the electric circuit for the unit.

The electric circuit

Electric current supply lines 1, 2, extend to terminals 3, 4, on a fiber insulator block 5. From the terminal 3, a lead line 6 extends to a condenser 7, and in parallel therewith is a conductor line 8 to a coil 9 having an electromagnet core 10. From the terminal 4 a line 11 extends to a terminal 12 having an insulation mounting 13. From the mounting 13 is a stirrup 14 to a riser free end 15 having an insulation assembly 16 with an adjusting means 17. The intermediate drop portion of the stirrup 14 has a switch terminal 18 normally in contact with a terminal 19 of a spring tongue 20 having an insulation mounting 21.

The circuit from the terminal 12, thru the stirrup 14 to the closed switch 18, 19, is to the tongue 20. Therefrom it is completed by a line 22 to the coil 9. In parallel with the coil 9 between the terminal 3 and the tongue 20, is the condenser 7 having toward the terminal 3 the line connection 6 and toward the tongue 20 a line connection 23.

The enclosing mounting

A resonance transmitting wall 24, in a building, vessel or plane, engaged by screws 25, may mount a support or flange 26 having rivet connections 27 with a flare shell or housing 28 terminating in a ledge 29.

2

The yieldable mounting for the electromagnet

Ears 30 are diametrically opposed and inward from the flange 26, carry screws 31 to engage outwardly extending spring arms 32, assembled by a bolt 33 into the core 10. The bolt 33, in mounting the core 10 and the coil 9, extends thru the insulation block 5 and a J-shaped frame member 34, having its longer leg to a foot 35 provided with a screw 36 connecting a base ring 37. A vibration absorbing mounting is thus provided for the ring 37 as carried thru the arms 32.

The shorter leg of the member 34 ends in an outward portion 38 connected by a bolt 39 to complete the assembly of the base 37 with the arms 32.

Mounting and enclosing the diaphragm

In lieu of a projector, a perforate shield 40 may have screws 41 pass therethru to locate concentrically therein an insulation ring 42 against a diaphragm disk 43. The screws 41, in passing thru the diaphragm 43, pull the edges of the diaphragm against the outer or rim portion of the base 37, to pack a felt or compressible packing 44 against the ledge 29 as crowded theretoward by a flange 45 of the facing plate or shield 40. This provides a cushioning connection from the mounting flange 26 in the reverse way thereto than from the arms 32.

The operation of the circuit breaking switch

Centrally of the diaphragm 43, there is an insulation disk 46 from which extends an armature 47 toward the fixed core 10 in the coil 9. While the core 10 is fixed with the coil 9, the whole electromagnet assembly between the arms 32 and the cushioning at the ledge 29, is a vibration damped mounting. As a switch 48 is closed to cut in an electric current supply, the energized coil 9 overcomes the spring 20 to open the circuit.

The energized coil 9 causes the magnet or core 10 to serve as an actuator for the armature 47, thereby to flex the diaphragm 43 as peripherally held. In this flexing, the insulation disk 46 rides against the free end of the leaf spring or tongue 20 to move it toward the coil 9. This shifts the contact 19, fixed with the tongue 20, away from the contact 18, fixed with the stirrup 14. The actuator operation is thus resisted, not only by the spring of the diaphragm 43, or the resilience therein, but by that of the tongue 20. The single end adjustment means 17 may so locate the terminal 18 against the supplementary contact ter-

10 minal 19 that the opening of this normally-closed switch occurs more nearly to the point the armature 47 strikes the core 10. Due to this single adjustment of the spring steel diaphragm 43 there is some slight change in the duration of the horn operation as well as in quality and quantity of tone therefrom. With a 24 volt D. C. source, an 8 ohm coil 9 and a .25 microfarad condenser 7, a current of .4 ampere develops 725 cycles per second. The mounting may be upon an outlet box cover plate, or even against the inside wall of a submarine. The 725 cycle frequency develops sound values of 105 to 110 decibels at a distance of 3 ft.

15 In the general structure as disclosed, the current supply for energizing may be either alternating or direct, and with the voltage even up to 120 volts.

What is claimed and it is desired to secure by Letters Patent is:

20 An electric signal device adapted to be mounted on a resonant building structure, said device comprising a support, a coil, a core for the coil, a diaphragm, an armature mounted on the diaphragm, a housing extending from the support and about 25 the coil and providing peripheral yieldable con-

10 nection for positioning the diaphragm with the armature in normal spaced proximity from the core, a switch including a contact operated directly by the movement of the diaphragm-carried armature relatively to the coil, a frame mounting the switch independent of the diaphragm, yieldable arm means from the support, and means anchoring the arm means, frame, coil and core as a unit sufficiently fixed to hold normal signal device movement relatively to the support.
